UNITED STATES PATENT OFFICE.

RONALD F. McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

MECHANISM FOR USE IN INSERTING FASTENINGS.

1,135,955.

Specification of Letters Patent.

Patented Apr. 13, 1915.

Original application filed April 19, 1909, Serial No. 490,848. Divided and this application filed September 29, 1909, Serial No. 520,149. Renewed April 2, 1914. Serial No. 829,136.

To all whom it may concern:

Be it known that I, RONALD F. McFEELY, a citizen of the United States, residing at Beverly, in the county of Essex and State 5 of Massachusetts, have invented certain Improvements in Mechanisms for Use in Inserting Fastenings, of which the following description, in connection with the accompanying drawings, is a specification, like reference characters on the drawings indicating 10 like parts in the several figures.

This invention relates to mechanisms for handling fastenings and particularly to the tack supplying mechanism of a tacking apparatus.

The invention is embodied in a mechanism which forms part of a pulling-over machine of the type shown in United States Letters Patent No. 663,777 and it has for an object 15 to insure greater reliability in the delivery of tacks to the inserting point. In that machine the tacks are supplied to the tack holders, from which they are to be driven, while the holders are in a position retracted from 20 the work. These holders make a quick movement into tack inserting position and it is during this movement or at the instant of its abrupt termination that tacks are sometimes thrown out of the tack pockets or rise there- 25 in far enough so that they are not properly expelled and inserted into the work by the descent of the drivers. This is perhaps because the tacks stand in the pockets in an inclined position so that they shall be driven 30 on a slant inwardly toward the median line of the last.

A main feature of this invention consists in novel means for preventing the tacks being thrown out of their pockets during the 35 quickly effected inward movement of the tack holders to tack inserting position. The tacks are delivered to the tack pockets through a conductor section which moves inwardly with the tack holders and which, in accordance with the illustrated embodiment 40 of this feature of the invention, is provided at its foot with an extension adapted to overlie the mouth of the tack pocket. Positioning means for the conductor section comprises a stop arranged to be engaged by it 45 when the tack holder is moved to its outer, tack receiving position. This stop swings the conductor to position it with its tack channel in delivering relation to the tack

55 pocket. A spring pressed plunger is arranged to swing the conductor section into position with the extension covering the tack pocket as soon as the tack holder leaves tack receiving position.

The invention includes also details of construction and combinations of parts which will be understood in connection with the illustrated embodiment thereof which will be described, and then the invention will be pointed out in the claims.

65 Figure 1 is a perspective view of parts directly concerned with the illustrative embodiment of the invention; Fig. 2 is a side elevation partly in section of a sufficient portion of the pulling-over machine to show the 70 application of this invention thereto; Fig. 3 shows a relation of the parts after they have left tack receiving position.

The tack arm 2 having the tack holder 4 at its lower end is swung from the frame at 5 75 and is actuated inwardly and outwardly by means guided in the frame at 6 and which may be understood by reference to said prior patent. The tacks are delivered from a conductor 8, the lower end of which is clamped 80 to the frame, into a conductor section 10 which moves inwardly with the tack arm to which it is pivotally connected at 12. The machine frame carries an adjustable stop 13 which is engaged by the heel end of the sec- 85 tion 10 when the tack arm is swung out- 90 wardly to tack receiving position against the stop 14 and by this engagement the conductor section is turned about its pivot 12 to raise its lower end and put the tack passage 95 thereof into delivering relation to the pocket of the tack holder, as shown in Figs. 1 and 2, so that a tack coming down the conductor 100 is freely delivered into the tack pocket. The conductor section 10 has a lip or projection 15 at its lower end and when the tack arm moves away from tack receiving position the conductor section leaves contact with the stop 13 and swings downwardly and back- 105 wardly about its pivot to cause the lip 15 to cover the mouth of the tack pocket as in Fig. 3 and preclude the possibility of a tack being thrown out of the pocket. Gravity may be relied upon to cause the covering move- 110 ment of the conductor section but in order to prevent loose swinging of the conductor section 12 a spring pressed plunger 16 is mounted in the tack arm and provided with

a head of substantial extent which may depend below the pivot 12 and, by its engagement at both sides of the pivot, steady the section effectively. The upper face of the 5 lip 15 is inclined and located close to the ends of the tack driver 18 so that the latter shall slide down the incline when it starts to descend and rock the conductor backwardly out of the path of the driver into the tack 10 pocket.

The operation of the several parts will be understood from the foregoing description of their construction and arrangement.

This application is a division of application Ser. No. 490,848, filed April 19, 1909, for improvements in pulling-over machines and in the present drawings are shown certain novel features of the last supporting and upper clamping and wiping mechanism of the machine the claims for which are made in the earlier application.

Having explained the nature of this invention and described a preferred embodiment thereof, I claim as new and desire to 25 secure by Letters Patent of the United States:—

1. A machine of the class described having tack inserting mechanism including a driver, tack supplying means, a tack block 30 adapted to hold a tack for the inserting action of the driver thereon and movable from receiving relation to the supplying means into delivering relation to the driver, and additional means for covering the tack contained in the holder during such movement.

2. A machine of the class described having, in combination, a tack driver, a tack holder movable between tack receiving and tack driving positions and having a tack 40 pocket, and additional means presenting a cover over the tack pocket at the termination of the movement of the holder into tack-driving position to prevent the tack from being thrown from the pocket and having a movement independent of the movement of the holder to uncover the pocket for the action of the driver on the tack.

3. A machine of the class described having, in combination, a tack holder movable 50 between tack receiving and tack delivering positions and having a tack pocket, a driver, a tack conductor section movable with the tack holder and means for shifting said conductor section automatically from a position with its channel in delivering relation to the tack pocket to a position in which an end face of the conductor covers the mouth of the tack pocket to prevent the escape of the delivered tack.

4. A machine of the class described having, in combination, a tack holder movable

between tack receiving and tack delivering positions and having a tack pocket, a driver, a tack conductor having a member to cover the tack pocket and movable automatically 65 to a central position to deliver tacks to the pocket and from said central position to one side of such central position to cause the cover to overlie the pocket and having an additional movement to permit the driver 70 to operate.

5. A machine of the class described having, in combination, a tack holder having a tack pocket, a driver, a conductor, means to hold the conductor in delivering relation 75 to the pocket, yielding means to move the conductor into position to prevent the tack being thrown out of the pocket and arranged to permit the driver to move the conductor aside to allow the driver to enter the tack 80 pocket.

6. A machine of the class described, having, in combination, a tack holder, a tack driver, the conductor 10 having the extension 15, the member 16 for yieldingly moving the conductor into position for the extension to cover the tack pocket, and the member 13 for reversely moving the conductor and positioning it to deliver a tack 85 in the tack pocket.

7. A machine of the class described, having, in combination, a tack holder movable between tack receiving and tack delivering positions and having a tack pocket, a driver, and a tack conductor adapted to have a tack 95 delivering and a tack covering relation to the tack pocket, said machine having provision for automatically actuating the conductor for the purposes stated.

8. A machine of the class described, having, in combination, a tack pocket, a pivoted conductor movable from tack delivering relation to tack covering relation to the pocket, and a yielding member arranged to maintain the conductor in a predetermined relation 100 to the pocket.

9. A machine of the class described having, in combination, a tack tube, a pivotally mounted conductor section movable from and toward position to receive a tack from 110 the tube, and means for automatically turning said section about its pivot to center it relatively to the tube and maintain its predetermined angular position during the tack delivering operation.

In testimony whereof I have signed my name to this specification in the presence of two subscribing witnesses.

RONALD F. McFEELEY.
